THRESHER

Lee P. Millard and Stuart D. Pool, Moline, Ill.,
assignors to International Harvester Company,
a corporation of New Jersey

Application August 8, 1941, Serial No. 405,980

7 Claims. (Cl. 130—27)

This invention relates generally to threshers and is particularly concerned with a novel drive and adjustment for the threshing cylinder.

An important object of the present invention is the provision of a novel speed change device for the thresher cylinder.

Another important object of the present invention is the provision of novel means for adjusting the cylinder and the speed change device with respect to the cylinder concave.

According to the present invention, a cylinder shaft and a transverse jack-shaft are journaled in frame structure that is movably mounted adjacent each of the separator side sheets. Adjustable mating pulley sections are mounted in alignment on the cylinder and jack-shaft. A novel manually adjustable means is operatively associated with each of the mating pulley sections in such a manner that the belt that is trained around said sections is always maintained in a straight line when the pulley sections are adjusted to change the cylinder speed. A manually adjustable means operatively connects the frame structures and the separator for adjusting the frame structures toward or away from the cylinder concave. This adjustment does not affect the speed of the cylinder, since the cylinder and jack-shaft are maintained in spaced relation by the frame structures.

These and other objects and advantages of the present invention will be apparent to those skilled in the art after a consideration of the following detailed description of the preferred structural embodiment, taken in conjunction with the accompanying drawings.

In the drawings:

Figure 1 is a side view of a thresher separator and shows the novel frame structures in which the cylinder and jack-shaft are journaled and the novel adjusting means for said structures;

Figure 2 is a sectional view taken along the line 2—2 of Figure 1 and shows the adjustable mating pulley sections for the cylinder shaft and jack-shaft; and,

Figure 3 is a sectional view taken along the line 3—3 of Figure 1 and shows the means for guiding and securing the frame structures to the separator side sheets.

Referring now to the drawings, it will be noted that the thresher chosen to illustrate the principles of the present invention comprises vertical spaced side sheets 11 and 12 that are connected at their upper edges by a top 13. The side sheets 11 and 12 are re-enforced by vertical

angle bars 14. The usual concave 15 is secured between the sheets 11 and 12.

On the outside of each of the side sheets 11 and 12 is movably mounted a frame structure 17 which comprises bearing plates 18a, 18b, 19a, and 19b. As shown in Figure 2, the frame structures 17 are positioned adjacent the side sheets 11 and 12. Spaced elongated openings 11a and 11b are provided in the side sheets 11, and spaced openings 12a and 12b are provided in the side sheet 12. The openings 11a and 11b are in alignment with the openings 12a and 12b. Each of the bearing plates 18a, 18b, 19a, and 19b is provided with a bearing 20 that extends through the openings provided in the side sheets 11 and 12. This construction is shown in Figure 2. Referring now to Figure 1, it is to be noted that the bearing plate 18a has a pair of angle bars 21 secured thereto, which extend toward the bearing plate 18b, and the bearing plate 18b has a pair of angle bars 22 secured thereto, which extend toward the bearing plate 18a. The angle bars 21 and 22 are positioned adjacent one another and are secured together by bolts 23. The bearing plates 19a and 19b are also provided with angle bars 24 and 25 that are secured together by bolts 26.

The bearing plates 18a and 18b are held adjacent the side sheet 12 by means of guide plates 27 which are secured to the sheet 12 by bolts 28. As shown in Figure 3, opposite edges of the plates 18a and 18b are provided with a bead portion 29 over which a bead portion 30 of the guide plate 27 fits. Similar side plates 27 are provided for the bearing plates 18b, 19a, and 19b.

In the bearings 20 provided in the bearing plates 18a and 18b is journaled a jack-shaft 31 which extends outwardly beyond each of the side sheets 11 and 12. On the right-hand end of the jack-shaft 31 is secured a sprocket 32 which may be driven from any suitable source of power for the machine. On the left-hand end of the jack-shaft 31 is mounted an adjustable pulley 33 which comprises mating pulley sections 34 and 35. A manually adjustable means 36 consisting of a hand wheel 37 and a cylindrical portion 38 is journaled on the jack-shaft 31. The periphery of the cylindrical portion 38 is provided with right- and left-hand threads 39 and 40. The pulley section 35 has a threaded opening 41 at its center which is turned on the threaded portion 39 of the cylindrical portion 38, and the pulley section 34 has a threaded opening 42 which is turned on the threaded portion 40 of said portion 38. The hand wheel 37 adjusts the pulley sections

34 and 35. These sections, however, are slidably mounted on a supporting means 43 which comprises a portion 44 that encircles the shaft 31 and is fixed thereon by a set screw 45. Tubular members 46 extend from the supporting means 43 and are arranged parallel to the shaft 31. The members 46 extend through suitable openings 47 provided in the pulley sections 34 and 35.

The pulley sections 34 and 35 may be adjusted toward and away from one another by rotating the hand wheel 37 which in turn rotates the cylindrical portion 38. Since the pulley sections are in threaded engagement with the cylindrical portion 38, the pulley sections are moved toward or away from one another on the supporting means 43.

In the bearings 28 provided in the bearing plates 18b and 19b is journaled a shaft 48 on which is secured the usual threshing cylinder 49 that cooperates with the concave 15. The shaft 48 extends outwardly beyond the side sheet 12 and an adjustable pulley 33a is mounted thereon which is identical to the pulley 33 with the exception that it is of different diameter. Since the pulley 33 has been described in detail, the same reference numerals with the letter *a* affixed will denote similar parts, and its construction will not be described again.

A belt 50 is trained around the adjustable pulleys 33 and 33a. This belt drives the shaft 48 from the driven jack-shaft 31.

It is desirable many times to change the speed of the cylinder 49. By the structure just described, the speed of the cylinder may be quickly and easily changed. To effect this adjustment, the hand wheel 37a is rotated so that the pulley sections 34a and 35a are moved away from each other. This movement of the pulley sections 34a and 35a slackens the belt 50. The handwheel 37 is then rotated so that the pulley sections 34 and 35 are moved toward one another until the belt 50 is again taut. Since the pulley sections of each speed change device are moved with respect to one another, the belt 50 is maintained in a straight line position at all times, as shown in Figure 2.

After the adjustable pulleys 33 and 33a have been adjusted to the desired position, they are locked to the shaft on which they are mounted. Referring to Figure 2 and to the adjustable pulley 33, it will be noted that the end of the jack-shaft 31 is provided with a reduced diameter threaded portion 31a on which a washer or collar is mounted. The washer 51 contacts the end of the hand wheel 37, and the nuts 52 turned on the portion 31a clamp the cylindrical portion 38 between the washer 51 and the portion 44 of the supporting means 43. The adjustable pulley 33a is clamped to the shaft 48 in the same manner.

The frame structures 17 provided at each side of the separator 10 may be moved so as to change the distance between the periphery of the cylinder 49 and the concave 15. This adjustment is desirable, since sometimes the crop is heavy and a greater distance must be provided between the cylinder periphery and the concave. Sometimes the crop is light and consequently the cylinder periphery must be moved close to the concave to insure the proper threshing of the crop.

At the upper edge of each of the plates 18a and 19a is secured a rod 53 which extends upwardly through an opening provided in a bracket 54 that is secured to the separator 10 and the upper edge of the vertical angles 14. The free end of each of the rods 53 is provided with threads on which are turned nuts 55, one at each side of the bracket 54. When the cylinder 49 is to be adjusted rela-

tive to the concave 15, the nuts 55 are loosened. If the cylinder 49 is to be lowered, the bolts 28 of the bearing plates 18a, 18b, 19a, and 19b may be loosened. However, these bearing plates may be a slip fit in the guide plates 27 and 27a. The upper nuts 55 are loosened. The weight carried by the frame structure under most conditions is sufficiently great to lower the cylinder 49. In the event there is some grain between the cylinder 49 and the concave 15, the lower nuts 55 may be tightened against the bracket 54 to force the frame structures 17 toward the concave 15. The bolts 28 are then tightened. If the cylinder is to be raised, the upper nuts 55 are first loosened, and then the lower nuts 55 are tightened to raise the frame structures 17.

From the foregoing description it should be apparent that a novel drive has been provided for the thresher cylinder. The drive embodies novel means for quickly and easily changing the speed of the cylinder. Further, a novel means is provided for adjusting the thresher cylinder relative to the concave. This adjustment may be made without disturbing the speed of the cylinder.

While only a preferred construction embodying the principles of the present invention has been shown and described, it is to be understood that the invention is not to be limited to the specific details shown and described, but that, in fact, widely different means may be employed in the practice of the broader aspects of the invention.

What is claimed is:

1. In a thresher comprising a housing, a concave, a cylinder, a cylinder shaft carrying the cylinder, a jack-shaft, and means connecting the jack-shaft with the cylinder shaft for transmitting drive from the jack-shaft to the cylinder shaft and for varying the ratio of the speed of the cylinder to the speed of the jack-shaft, the combination therewith of means for adjusting the spacing between the cylinder and the concave and maintaining the spacing between the jack-shaft and the cylinder shaft, said means comprising a frame structure rotatably supporting the jack-shaft and the cylinder shaft and means adjustably securing the frame structure to the housing for conjointly adjusting the jack-shaft and the cylinder shaft with respect to the concave.

2. In a thresher comprising a housing having spaced side sheets, a concave, a cylinder, a cylinder shaft carrying the cylinder, a jack-shaft, and means connecting the jack-shaft with the cylinder shaft for transmitting drive from the jack-shaft to the cylinder shaft and for varying the ratio of the speed of the cylinder to the speed of the jack-shaft, the combination therewith of means for adjusting the spacing between the cylinder and the concave and maintaining the spacing between the jack-shaft and the cylinder shaft, said means comprising frame structures rotatably supporting the jack-shaft and the cylinder shaft and means adjustably securing the frame structures to the side sheets of the housing for conjointly adjusting the jack-shaft and the cylinder shaft with respect to the concave.

3. In a thresher comprising a housing having a top and a side, a concave mounted in the housing, a cylinder positioned over the concave, a cylinder shaft carrying the cylinder, a jack-shaft positioned above the cylinder shaft and below the top of the housing, and means connecting the jack-shaft and the cylinder shaft for transmitting drive from the jack-shaft to the cylinder shaft and for varying the ratio of the speed of the cylinder to the speed of the jack-shaft, the

combination therewith of means for adjusting the spacing between the cylinder and the concave while maintaining the spacing between the jack-shaft and the cylinder shaft, said means comprising a frame structure rotatably supporting the jack-shaft and the cylinder shaft and means adjustably securing the frame structure to a point of the housing adjacent the top thereof for conjointly adjusting the jack-shaft and the cylinder shaft with respect to the concave.

4. In a thresher comprising a housing having a top and spaced side walls, a concave mounted in the housing, a cylinder positioned over the concave, a cylinder shaft carrying the cylinder, a jack-shaft positioned above the cylinder shaft and below the top of the housing, and means connecting the jack-shaft and the cylinder shaft for transmitting drive from the jack-shaft to the cylinder shaft and for varying the ratio of the speed of the cylinder to the speed of the jack-shaft, the combination therewith of means for adjusting the spacing between the cylinder and the concave while maintaining the spacing between the jack-shaft and the cylinder shaft, said means comprising a frame structure rotatably supporting the jack-shaft and the cylinder shaft, and means adjustably securing the frame structure to a point of the housing adjacent the top thereof for conjointly adjusting the jack-shaft and the cylinder shaft with respect to the concave.

5. In a thresher comprising a housing having a top and spaced side walls, a concave mounted in the housing, a cylinder positioned over the concave, a cylinder shaft carrying the cylinder, a jack-shaft positioned above the cylinder shaft and below the top of the housing, and means connecting the jack-shaft and the cylinder shaft for transmitting drive from the jack-shaft to the cylinder shaft and for varying the ratio of the speed of the cylinder to the speed of the jack-shaft, the combination therewith of means for adjusting the spacing between the cylinder and the concave while maintaining the spacing between the jack-shaft and the cylinder shaft, said means comprising frame structures slidably mounted in the side walls of the housing for movement toward and away from the concave and rotatably supporting the jack-shaft and the cylinder shaft and means adjustably securing the frame structures to points on the housing at the juncture of the side walls with the top for conjointly adjusting the jack-shaft and the cylinder shaft with respect to the concave.

6. In a thresher comprising a housing having a side wall, a concave mounted within the housing, a cylinder positioned adjacent the concave, a cylinder shaft carrying the cylinder, a jack-

shaft, means connecting the jack-shaft and the cylinder shaft for transmitting drive from the jack-shaft to the cylinder shaft, the combination therewith of means for adjusting the spacing between the cylinder and the concave and maintaining the spacing between the jack-shaft and the cylinder shaft, said means comprising a first plate slidably mounted on the side wall and rotatably supporting the cylinder shaft, guide means associated with opposite edges of the first plate and with the side wall of the housing for limiting sliding of the first plate along the side wall to a direction toward and away from the concave, a second plate slidably mounted on the side wall and rotatably supporting the jack-shaft, guide means associated with opposite edges of the second plate and with the side wall of the housing for limiting sliding of the second plate along the side wall to a direction toward and away from the concave, means tying the plates together to secure them against relative movement, and means adjustably securing the plates to the housing for conjointly adjusting the jack-shaft and the cylinder shaft with respect to the concave.

7. In a thresher comprising a housing having a top and spaced side walls, a concave mounted in the housing, a cylinder positioned over the concave, a cylinder shaft carrying the cylinder, a jack-shaft positioned above the cylinder shaft and below the top of the housing, and means connecting the jack-shaft and the cylinder shaft for transmitting drive from the jack-shaft to the cylinder shaft and for varying the ratio of the speed of the cylinder to the speed of the jack-shaft, the combination therewith of means for adjusting the spacing between the cylinder and the concave while maintaining the spacing between the jack-shaft and the cylinder shaft, said means comprising frame structures slidably mounted on the side walls of the housing and rotatably supporting the jack-shaft and the cylinder shaft, each frame structure including a plate, guide means associated with opposite edges of the plates for limiting sliding of the plates to a direction toward and away from the concave, and means adjustably securing the frame structures to the housing for conjointly adjusting the jack-shaft and the cylinder shaft with respect to the concave, said means comprising brackets secured at opposite sides of the housing at the junctures of the side walls and the top of the housing, bolts secured to the frame structures and extending through the brackets and nuts threaded on the bolts and engaging the brackets to determine the position of the bolts with respect to the brackets.
